UNITED STATES PATENT OFFICE.

VICTOR OLSEN AND OTTO DAMM, OF DETROIT, MICHIGAN.

METALLIC AND GLASS CONSTRUCTION.

982,015.

Specification of Letters Patent. Patented Jan. 17, 1911.

Application filed October 27, 1909. Serial No. 524,997.

To all whom it may concern:

Be it known that we, VICTOR OLSEN and OTTO DAMM, who are citizens of the United States, residing at Detroit, county of Wayne, 5 State of Michigan, have invented a certain new and useful Improvement in Metallic and Glass Construction, and declare the following to be a full, clear, and exact description of the same, such as will enable others skilled in the art to which it pertains to 10 make and use the same, reference being had to the accompanying drawings, which form a part of this specification.

This invention relates to combined metallic and glass construction of the type especially adapted for ornamental ceilings, and has for its object an improved means for holding in place selected and especially prepared squares or other shaped tablets of 15 glass in desired position with respect to one another and to the supporting members therefor, with the interposition between the glass and the eye of the observer of as little fastening material as possible, the glass, however, being spaced below the level of the 20 supporting ceiling beams.

In the drawings:—Figure 1, is a sectional elevation of one of the finishing rosettes and glass-holding strip; together with the adjacent edges of glass and the wooden support to which it is fastened. Fig. 2, is a plan view of the meeting corners of adjacent sections of glass with the finishing rosette in place thereover. Fig. 3, is a plan from 25 beneath a section of ceiling, showing several sections of glass held in place by the means described. Fig. 4, is a sectional elevation of the metal-supporting strip or beam and of the glass-holding clip in its initially attached position thereon. Fig. 5, is a perspective of the channeled glass-holding strip.

I indicates the supporting beam slightly spaced, from the under face of which are intended to be supported the meeting edges of 45 two lights or tablets of glass 2 and 3.

4 is a channeled metal chamber, somewhat resembling a U in cross section, which is adapted to be nailed or screwed to the beam I with its fastening portion 5 against the 50 under portion of the beam I by nails or small screws 6. After the glass has been placed against either of the flange members 7 and 8, the clip portions 9 and 10 of this member 4 are bent over so as to engage under the 55 edge of the glass, that is, on the opposite face from that engaged by the flange 7 or

8. These strips, meeting as they do at the points of intersection of their supporting beams with similar ones, running usually at right angles to them have their meeting ends 60 covered in the first instance by a filler piece 11, which, in turn, is covered by the ornamental rosette 13; through both of these engages the screw 15, which in addition extends through the depth of the member 4 65 and into the supporting strip 1. Either the filler piece 11 or the rosette 13 may be omitted without departing from the proper scope of my invention, or, instead of the rosette, an electric light fixture with its 70 rosette covering the meeting ends of the metal strip may be installed, the concave portion of the strip 4 being especially adapted to contain electric wires therewithin. Or, if desired, the nails 6 may be omitted and 75 the support given thereto be concentrated at the ends, where the rosettes and holding screws are located. One of these rosettes 6 extends over the meeting corners of four squares, each of which is so located and so 80 shaped as to have its other three corners similarly held in relation to adjacent corners of the other squares of glass.

What we claim is:—

1. In combination with a supporting beam 85 member, a metal member of trough shaped cross section adapted to engage against one face of said beam, said member having its outer flanged edge portions cut into a plurality of sections independent of one another, though retaining their connection with the body portion of the metal member, and said sections being alternatingly bent 90 into a position of coincidence with one of two planes substantially parallel with the adjacent face of the beam member; a pane of glass adapted to have its edge portions inserted between the two series of flanged sections along the edge of the metal member, a filler member having a broad head engaging within the troughed portion of the metal member, and a correlating screw extending through said metal member and said filler member into said beam member, substantially as described. 100

2. The combination of a supporting beam, a pane of glass whose support out of contact therewith is desired, a channeled metal member supported from said beam, said member having flanged edge portions divided into a plurality of sections and adapted to be bent alternatingly against the edge 105 110

portions of the opposing faces of said pane of glass, a filler member engaging against the inner face of said channeled member at its ends, a rosette member engaging there-over, and a correlating holding screw extending therethrough into the body of the beam, substantially as described.

3. In combination with a supporting beam, a pane of glass, channeled members having its central web portion attached to said beam, each member having flanging edge portions between alternating parts of which said pane of glass is inserted, being held

by said parts at a distance from the point of attachment of the channeled member to 15 the beam, and means engaging over the meeting ends of adjacent channeled members for correlating the same, substantially as described.

In testimony whereof, we sign this specification in the presence of two witnesses.

VICTOR OLSEN.
OTTO DAMM.
